UNITED STATES PATENT OFFICE.

CLARE NELSON, OF BROOKLYN, NEW YORK, ASSIGNOR, BY MESNE ASSIGNMENTS, TO
CHARLES C. ORCUTT, OF NEW YORK, N. Y.

PAPER-DRYING MACHINE.

Application filed April 13, 1922. Serial No. 552,173.

To all whom it may concern:

Be it known that I, CLARE NELSON, a citizen of the United States, residing at Brooklyn, in the county of Kings, State of New York, have invented certain new and useful Improvements in Paper-Drying Machines; and I do hereby declare the following to be a full, clear, and exact description of the invention, such as will enable others skilled in the art to which it appertains to make and use the same.

My invention is an improvement in paper drying machines, and relates particularly to means for correcting the tendency to side slip in paper supporting belts or aprons of the character shown and described in applications, Serial No. 356,669, filed February 6, 1920, and Serial No. 434,231, filed December 31, 1920.

Machines of this character are designed to dry the paper quickly, and the paper is so supported in its passage through the machine, that a minimum of obstructions is offered to the free circulation of the heated air, at both faces of the paper. To attain this end, a support is provided which engages the paper over restricted areas relatively close set, preferably a support of wire cloth or screen, so woven, that each face thereof presents a series of parallel grooves, separated by and alternating with ribs. The ribs are not continuous, but are broken, each rib being composed of many alined projections. The cloth or screen is woven on the bias, and the ribs and grooves are inclined with respect to the length of the belt, and to the direction of its travel. Hence the ribs meet the peripheries of the supporting rollers for the apron at an angle, and a continuing lateral stress is exerted, which tends to displace the apron laterally and longitudinally of the rollers.

The object of the present invention is to provide means for counteracting the tendency of the apron toward lateral movement, by setting up a continuing stress acting to displace the apron in the opposite direction.

In the drawings:

Figure 1 is a diagrammatic sectional view showing one embodiment of the invention.

Figure 2 is a partial plan view, with a part of the upper run of the apron broken away,

Figure 3 is a longitudinal section of a dryer unit provided with the apron, and

showing an alternate method of counteracting side slip,

Figure 4 is a partial plan view of one of the rollers with the apron in place,

Figure 5 is a similar view with the apron removed,

Figure 6 is an enlarged sectional detail of the roller and apron.

In the embodiment of the invention shown in Figures 1 and 2, the belt or apron 1 is composed of wire mesh, and woven on the bias, as shown in Figure 2. The apron is so woven, that each face thereof presents a series of grooves, separated by broken ribs, each rib comprising a number of alining projections. The projections on the upper run of the apron engage the paper to be supported, over restricted areas relatively close set, so that the heated air may have free access to the under face of the paper.

Because of the bias weave of the cloth, the ribs are inclined with respect to the length of the apron, and to the direction of its movement, and because of this inclined arrangement of the ribs, they meet the peripheral surfaces of the rollers 2, upon which they are supported, at an angle, and there is a camming action, between the ribs and the roller surface, which tends to slip the apron laterally on the rollers. Such side slip is objectionable for many reasons, and in order to counteract the same, I provide means for exerting a continuing stress acting to displace the apron in the opposite direction.

The said means in the construction of Figures 1 and 2, is a pair of similar rollers 3, which are arranged to engage the opposite face of the apron, from that which is engaged by the rollers 2. In the present instance these rollers 3 are of the same diameter as the rollers 2, and they engage the lower face of the under run of the apron, which is the opposite face from that engaged by the rollers 2. With such arrangement, the rollers 3 exert a camming action on the apron, in the opposite direction to the action exerted on the apron by the rollers 2, since the ribs on the inner face of the apron are inclined in the opposite direction to those on the outer face of the apron, and there is thus provided equal stresses acting to displace the apron in opposite directions, and counteracting each other.

In the construction of Figures 3 to 6, the apron is shown in connection with a heater 110

casing 4, the upper run of the endless belt or apron 5, passing through the casing, longitudinally thereof. The apron is supported by rollers 6 at the ends of the casing, 5 and the lower run, which is below the casing, is tensioned by a roller 7. One of the rollers 6, has sliding bearings 8, which are movable in guides, and are moved by screws 9, and by means of these screws, the roller 6 may 10 be moved toward or from its companion roller, to tension the apron 5. It is obvious, however, that the entire apron might be arranged within the casing if desired, or 15 that any other suitable arrangement of rollers might be provided. In order to counteract the tendency of the apron toward side slip, I provide one or both of the supporting rollers 6 with a series of substantially parallel spirally extending grooves 10, forming 20 between them elevated ribs 11. These ribs incline in the opposite direction to those of the adjacent face of the apron, and they tend to move the apron in the opposite direction to that in which it is moved by the camming 25 action between the ribs of the apron and the roller. The ribs 11 need not be inclined at the same angle as the ribs of the apron, and in practice it is possible that a much less inclination of the ribs of the roller will be 30 sufficient to counteract the side slip. The ribs are rounded, as shown more particularly in Figure 6, and they do not interfere with the free passage of the apron. In both arrangements, means is provided for exerting 35 stress upon the apron in the opposite direction to that exerted by the supporting roller.

I claim:

1. In a machine of the class described the combination of an endless belt or apron of fabric woven on the bias and having paper-engaging surfaces arranged in lines on its opposite faces, the said lines being inclined with respect to the longitudinal axis of the belt and those on one face being oppositely 45 disposed with respect to those on the other, a roller for moving said apron and by its contact with the apron tending to move the latter laterally in one direction, and a second roller engaging said apron and arranged to 50 exert a continued lateral stress on said apron in a direction opposite to that in which the roller first named tends to move the apron.

2. In a machine of the class described the combination of a paper-supporting apron 55 having on each face engaging surfaces of restricted area and relatively close set, arranged in lines inclined to the direction of travel of the apron, the inclination of the lines on one face being opposite to the inclination of the lines on the other, a roller for supporting and moving the apron and by its contact with the engaging surfaces of the apron tending to move the latter laterally 60 in one direction, and a second roller engaging said apron and arranged to exert a

continuing lateral stress on said apron in a direction opposite to that in which the roller first named tends to move the apron.

3. In a machine of the class described the combination of a paper-supporting apron 70 having substantially parallel paper-engaging ribs on its opposite faces inclined with respect to the direction in which the apron is to move, the ribs on one face inclining in the opposite direction to those on the other face, rollers engaging one face of the apron for moving the latter and by their contact with said face tending to move the apron laterally in one direction, and a second set of rollers engaging that face of the apron 80 opposite to the one engaged by the rollers first mentioned and exerting a lateral stress upon the apron opposite to that exerted by the rollers first named.

4. In a machine of the class described, the combination of a paper-supporting apron of wire cloth woven on the bias to provide substantially parallel paper-engaging ribs on each face inclined with respect to the direction of travel, the ribs on one face being inclined in the opposite direction to those on the other face, a pair of rollers disposed within the apron for moving the latter and by their contact with the ribs of the apron tending to move the apron laterally in one 95 direction during its forward movement, and rollers disposed outside of the apron and by their contact with the ribs of the apron exerting a uni-directional lateral stress upon the apron opposite to that exerted by the 100 rollers first named.

5. In a machine of the class described the combination of a belt or apron provided with a plurality of inclined lines or paper-engaging ribs on either face, the lines being inclined in opposite directions on the opposite faces, rollers within the apron for moving the same and by their contact with said ribs tending to move the apron laterally during its forward movement, and rollers located outside of the apron and having substantially the same diameter as the rollers first named, the rollers of the second group by their contact with the ribs on the face opposite to that engaged by the rollers first named serving to exert a uni-directional lateral force upon the apron opposite and equal to that exerted by said first named rollers.

6. In a machine of the class described, the combination of a paper-supporting apron having substantially parallel paper-engaging ribs on its faces, the ribs being inclined with respect to the direction of travel of the apron and having opposite inclinations 115 on the opposite faces of the apron, a roller for moving the apron arranged to engage the ribs on one face thereof and continuously exerting a uni-directional lateral stress 125 on the apron, and another roller engaging 130

the apron and having a plurality of substantially parallel spiral grooves arranged on its face, these grooves contacting with the ribs of the apron and exerting a unidirectional lateral stress on the apron opposite and equal to that exerted by the roller first named.

7. In a machine of the class described, a belt or apron formed with a plurality of inclined paper-engaging ribs on its opposite faces, the inclinations of the ribs on one face being opposite to those on the other, a roller for moving and supporting the apron, this

roller by its contact with the said ribs tending to force the apron laterally in one direction continuously, and another roller having a plurality of spiral grooves formed in its surface for engaging the same face of the apron as is engaged by the roller first mentioned, the spiral grooves in the second roller being formed to exert a continuous unidirectional stress on the apron opposite and equal to that exerted by the first roller.

In testimony whereof I affix my signature.

CLARE NELSON.
